PELLET MILL DIE AND METHOD OF
FORMING SAME

Jack L. Mitchell, Muscatine, Iowa, assignor to California
Pellet Mill Company, a corporation of California
Filed May 15, 1961, Ser. No. 110,167
2 Claims. (Cl. 18—12)

My invention relates to dies and more particularly to dies of the type employed in pellet mills for the pelleting of material, and method of forming same.

In pellet mills of the type to which the present invention relates, material to be pelleted is fed to the compression side of the die, over which an extrusion means, such as one or more extrusion rolls, travels by relative motion between the die and the rolls, to pressure the material through the die holes, for extrusion from the discharge side of the die, at which side the extrusions are severed to produce the pellets.

It has been the common experience that in such extrusion of materials, a certain amount of material, regardless of the surface of the extrusion roll, is squeezed out laterally from the path of the roll, in the absence of other factors, with the result that extrusion is not uniform from the discharge side of the die, and along those sections of the die where extrusion is most efficient, wearing of the compression side of the die becomes greatest.

Where the die is of the type whose compression surface lies in a horizontal plane, a certain amount of the material will escape sideways in the pelleting operation, from both sides of the roll, with the result that more material will be extruded through the holes located in the central region of the die than toward the outer edges of the die. Under these conditions, the die will wear at a faster rate at the center thereof than in the outer edge regions, and consequently the die will wear concave and become useless while there is still a great deal of usable lift left in the outer edge regions.

In a different type of pellet mill wherein the die forms the side walls of a die bowl and the die holes are horizontal, the extrusion rolls traverse the inner vertical wall of the die. In this type of mill, material deposited in the die bowl will be extruded most efficiently through the lower rows of die holes, due to the effect of gravity and the fact that the floor of the bowl will tend to block excessive escape of material from the lower edge portion of an extrusion roll, while material will be free to escape beyond the upper edge portion of such roll. Accordingly, in this type of mill, the wear on the die will be excessive over the lower rows of die holes.

Among the objects of the present invention are:

1. To provide a novel and improved pellet mill die;
2. To provide a novel and improved pellet mill die having an extended useful life expectancy;
3. To provide a novel and improved pellet mill die having a greater and more uniform output;
4. To provide a novel and improved pellet mill die having more uniform wear characteristics over the compression side of the die.

Additional objects of my invention will be brought out in the following description of a preferred embodiment of the same, taken in conjunction with the accompanying drawings, wherein the figure is a view in cross section through one form of pellet mill die, one in which the extrusion characteristics are substantially symmetrical with respect to the center line of the die.

In general, the problem of non-uniform wear and non-uniform production of conventional dies, as discussed previously, has been solved, in accordance with the present invention, by reducing the resistance to extrusion, of those die holes which are located in regions where pro-

duction would normally be less, the degree of reduction of such resistance being roughly in accordance with the deficiency in production normally experienced in a conventional die of like type and under similar conditions of use. The die, with the die hole resistances thus adjusted, will encourage substantially uniform feed of material to all the die holes, under operating conditions.

Referring to the drawing for details of my invention, the invention is shown as applied to a die 1, which may be circular in form, having a compression side 3 and a discharge side 5 with a plurality of circular rows of die holes 9 through the die from the compression side to the discharge side. The holes in the various rows will preferably be staggered with respect to the holes in adjacent rows in accordance with conventional practice, and further, in accordance with conventional practice, these holes may each be provided with a countersink 13 at the entrance thereto.

In cooperation with such die, there is customarily provided one or more extrusion rolls 15, each of which spans the rows of die holes, and traverses the compression side of the die, in the course of which, material deposited on the surface of the die will be pressed into the die holes and extruded from the discharge side of the die; and as is conventional practice, the extrusions as they emerge, will be periodically severed into pellets.

In accordance with the preferred manner of accomplishing the objects of the present invention, as applied to a die of the type illustrated in the drawings, those holes lying to either side of the central region of the die are relieved as by counter-boring the same at their discharge ends, to provide counter-bores 17 at the holes furthest removed from the central region of the die, of greater depth than counter-bores 19 associated with holes closer in toward the central region.

Thus, in the specific embodiment illustrated, I have shown a die with seven rows of holes in which the three center rows are of normal conventional design, while the holes in the outermost rows are counter-bored to one extent, and those holes closer in toward the central region are counter-bored to a lesser degree.

The provision of these counter-bores, produces a working section 23 in a counter-bored hole of less length than the working section 25 of the holes in the central region of the die, by an amount equal to the depth of the counter-bore, and by reason of this, decreases the resistance of such counter-bored holes, to the extrusion of material therethrough. This encourages the flow of material into these particular holes and thus, by judiciously determining the die holes to be counter-bored, and the depth thereof, so as to realize substantially equal rate of feed into all of the die holes, not only can be product of the die be made more uniform, but also the wear transversely of the die, which latter can result in a marked increase in life expectancy of the die. Actual experience with dies improved in accordance with the present invention, has indicated that the useful life of a die can be increased by as much as 60%.

While I have illustrated my invention in its preferred form, it will be apparent that the same is subject to alteration and modification without departing from the underlying principles involved, and I accordingly do not desire to be limited in my protection to the specific details and method illustrated and described, except as may be necessitated by the appended claims.

I claim:

1. In combination, a pellet mill die having a compression side uniformly spaced from said compression side, a discharge side adapted to be traversed by extrusion means, and a plurality of die holes through said die from said compression side to said discharge side and of like

diameter at the compression ends thereof, said die being of uniform thickness between its compression side and its discharge side, an extrusion roll in extrusion relationship to and adapted for movement over the compression side of said die, the holes in said die traversed by an edge portion of said roll being counter-bored at their discharge ends to reduce the resistance to extrusion of material therethrough as compared to the resistance offered by others of said holes traversed by an intermediate portion of said roll.

2. A pellet mill die having a compression side adapted to be traversed by an extrusion roll, a discharge side, and a plurality of die holes through said die from said compression side to said discharge side and of like diameter at the compression ends thereof, said die being of uniform thickness between its compression side and its dis-

charge side, and the holes in said die traversed by an edge portion of such roll being counter-bored at their discharge ends to reduce the resistance to extrusion of material thereto as compared to the resistance offered by other of said holes traversed by an intermediate portion of said roll.
